(57) **CLAIM**

The ornamental design for a light-emitting diode package, as shown and described.

DESCRIPTION

FIG. 1 is a top, front and left side perspective view of a light-emitting diode package showing my design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom, front and right side perspective view thereof.

1 Claim, 6 Drawing SheetsFIG. 1

FIG. 2

FIG. 3

FIG. 4

FIG. 5
